UNITED STATES PATENT OFFICE.

LLOYD J. HIBBARD, OF WILKINSBURG, PENNSYLVANIA, ASSIGNOR TO WESTINGHOUSE ELECTRIC & MANUFACTURING COMPANY, A CORPORATION OF PENNSYLVANIA.

SYSTEM OF CONTROL.

1,416,026.

Specification of Letters Patent.

Patented May 16, 1922.

Application filed May 14, 1920. Serial No. 381,279.

To all whom it may concern:

Be it known that I, LLOYD J. HIBBARD, a citizen of the United States, and a resident of Wilkinsburg, in the county of Allegheny and State of Pennsylvania, have invented a new and useful Improvement in Systems of Control, of which the following is a specification.

My invention relates to systems of control 10 for dynamo-electric machines and it has special relation to the acceleration of poly-phase induction motors and the like.

One object of my invention is to provide a system of the above-indicated character, 15 wherein a plural-section resistor is associated with the poly-phase-rotor winding of an induction motor, and sections of the resistor are progressively excluded from circuit in a certain rotation to effect a smooth 20 and uniform acceleration of the motor.

More specifically stated, it is the object 25 of my invention to provide a star-connected resistor device that is associated with the three-phase rotor winding of an induction motor, together with a plurality of switching devices for gradually cutting out resistance from each phase while maintaining a 30 substantial balance of currents between the several phases.

My invention may best be understood by 35 reference to the accompanying drawing, wherein—

Figure 1 is a diagrammatic view of the 40 main circuits of a system of control embodying my invention; and

Fig. 2 is a sequence chart of well-known 45 form serving to indicate the preferred order of operation of the various switches that are illustrated in Fig. 1.

Referring to Fig. 1, the system here shown 50 comprises a plurality of three-phase supply-circuit conductors 10, 11 and 12 to which are connected the star-related phase windings of the primary member 13 of an induction motor 14, which further comprises a wound rotor 15.

A plurality of brushes 16, 17 and 18 bear 55 upon the respective collector rings of the rotor 15 and are connected through conductors 19, 20 and 21, respectively, to a plurality of star-related resistors 22, 23 and 24 which may thus be considered as respectively connected in phase A, phase B and phase C, as indicated by the corresponding 60 legends.

A plurality of preferably electrically-operated or solenoid-type switches 1 to 6, inclusive, are associated in pairs with the respective resistor sections; and a plurality of cam-operated switches A1 to A8, inclusive, B1 to B8, inclusive, and C1 to C8, inclusive, are further adapted to be connected to various tap-points of the respective resistors. Considering the resistor 22, for example, line switch 1 has one terminal directly connected to the outer terminal of the resistor, while the other switch terminal is connected to one stationary terminal of each of the alternately-located switches A1, A3, A5 and A7. The solenoid or line switch 4 has one terminal connected to the outer end of the resistor 22, while the other terminal is connected to one terminal of each of the remaining cam-operated switches A2, A4, A6 and A8. The remaining sets of both 75 types of switches are associated with the corresponding resistors in a similar manner.

It will be understood that the particular 80 type of switches that I employ is immaterial to the present invention, although the cited combination of electrically-actuated and cam-operated switches makes for a convenient and inexpensive arrangement. Since both the structures and the method of effecting closure of the various switches are familiar 85 to those skilled in the art, I have not deemed it necessary to further illustrate the switches or to show any auxiliary governing system for closing them in the order specified by the sequence chart, Fig. 2.

Assuming that it is desired to effect acceleration of the induction motor 14, the proper switches are closed to connect the primary winding 13 across the supply-circuit conductors 10, 11 and 12 and to connect 95 the slip-rings 16, 17 and 18 to the outer ends of the resistors 22, 23 and 24, respectively, as illustrated, all of the switches that are directly associated with the resistors being initially open.

To increase the motor speed, the controlling device, of whatever character selected, is actuated one step forward to its position *a*, whereby the line switch 1 and the cam switches A1 and B1 are closed, as indicated 105 by the corresponding line in the sequence chart. The simultaneous closure of switches 1 and A1 short-circuits the outermost section or block of the resistor 22, thus permitting a corresponding increase in the cur- 110

rent traversing phase A of the induction-motor-secondary winding 15.

As soon as the controller is moved to position b, line switch 2 and cam switch C1 5 are closed. Since the switches 2 and B1 are now both closed, the outermost section or block of the resistor 23 is likewise short-circuited.

In position c, line switch 3 and cam switch 10 A2 are closed. In this way, the outermost section of the resistor 24 is short-circuited.

In other words, the first three steps of the controller serve to progressively exclude equal sections of resistance from the circuits 15 of all three-phase windings.

In position d, line switch 4 closes, and, since the cam switch A2 was closed in position c, an additional block of the resistor 22 is thus short-circuited. The switch B2 is 20 also closed in this position, and, as soon as the controller reaches position e, the closure of switch 5, conjointly with the switch B2, serves to short-circuit another section of the resistor 23.

25 Cam switch C2 is also closed in position e, and the subsequent closure of line switch 6 in position f causes another section of the resistor 24 to be excluded from circuit.

In this way, another uniform decrease of 30 resistance in all three of the phase-winding circuits is accomplished.

It will be noted that, in position e, the line switch 1 is opened, but this has no effect upon the circuit, since the two outermost sections of the resistor 22 are short-circuited by the switches 4 and A2 conjointly. Likewise, in position f, the line switch 2 and the cam switch A1 are opened, but again no change in the circuits is accomplished thereby, since 40 the other switches that have been closed serve to short-circuit the portions of the accelerating resistors that were originally short-circuited through the use of the switches 2 and A1.

45 The next progression is begun in this position f by reason of the closure of cam switch A3 which acts conjointly with switch 1 when the latter is closed in position g of the controller to short-circuit a further section of the resistor 22.

In position g, the line switch 3 and cam switch B1 are opened but no circuit changes are effected thereby, as will be understood from the analogous operation of these 55 switches with respect to those previously described.

Cam switch B3 is also closed in position g and serves, conjointly with line switch 2, which is closed in position h, to short-circuit 60 a third section of the resistor 23. Line switch 4 and cam switch C1 are opened in this position without changing the circuit values, while cam switch C3 is actuated to

close a gap in a new circuit which is completed in position i of the controller by the

closure of line switch 3. In this way, the third section of the resistor 24 is excluded from circuit and another progression has thus been accomplished.

Line switch 5 and cam switch A2 are 70 opened in position i, while cam switch A4 is closed.

It is believed that no further exposition of the operation of my invention is necessary, since the principles that are followed out 75 are considered to be clearly evident from the foregoing description. In general, the line switches, such as switches 1 and 4, that are associated with the resistor 22, are alternatively employed in conjunction with 80 the successively-arranged cam-operated switches A1, A2, etc., to exclude from circuit consecutive sections of the resistor, or, in other words, the active tap-point on the resistor is gradually shifted toward the star-point 85 25 to which the inner ends of all three resistors are directly connected. Thus, as soon as the line switch 4 and the cam switch A8 are closed, as indicated in step x, the entire resistor 22 is short-circuited and phase 90 A is thus traversed by current corresponding to the maximum available speed of the rotor 15.

During the gradual short-circuit of the resistor 22, as just set forth, the other resistors 23 and 24 are also progressively short-circuited, but the corresponding sections of resistance are excluded from circuit in a regular rotation or succession rather than simultaneously with the exclusion of 100 the corresponding sections of the resistor 22.

In this way, a smoothly progressive control of the rotor phase-winding currents is provided and a desirably steady and uniform acceleration of the induction motor 14 105 is afforded.

I do not wish to be restricted to the specific circuit connections or arrangement of parts herein set forth, as various modifications thereof may be effected within the 110 spirit and scope of my invention. I desire, therefore, that only such limitations shall be imposed thereon as are indicated in the appended claims.

I claim as my invention:

1. The combination with a plurality of resistors having a common terminal, of means including a plurality of sets of alternately-employed switches for progressively short-circuiting sections of said resistors in a predetermined rotation.

2. The combination with a plurality of resistors having a common terminal, of means including a plurality of sets of alternately-employed switches for progressively reducing in a predetermined rotation the active values of the resistors measured from said common terminal.

3. The combination with a plurality of resistors having a common terminal, of

means including a plurality of sets of alternately-employed switches for progressively short-circuiting sections of said resistors in a predetermined rotation, each set 5 of said switches having a common terminal connected to one end of a resistor.

4. The combination with a plurality of resistors having a common terminal, of means including a plurality of sets of alternately-employed switches for progressively reducing in a predetermined rotation the active values of the resistors measured 10 from said common terminal, each set of said switches having a common terminal connected to one end of a resistor.

5. The combination with a plurality of resistors having a common terminal, of means including a plurality of sets of alternately-employed switches for progressively short-circuiting sections of said resistors in a predetermined rotation, each set 20 of said switches having a common terminal connected to the outer end of a resistor.

6. The combination with a plurality of resistors having a common terminal, of means including a plurality of sets of alternately-employed switches for progressively reducing in a predetermined rotation the active values of the resistors measured 25 from said common terminal, each set of said switches having a common terminal connected to the outer end of a resistor.

7. The combination with a plurality of resistors having a common terminal, of a plurality of switching devices adapted to be 30 connected to different tap-points of each of said resistors, a plurality of sets of switches

adapted to be connected to different groups of said devices, the switches corresponding to any resistor being alternatively closed to effect a gradual short-circuit of that resistor and the said sets of switches and the devices being closed in a predetermined rotation to effect progressive control of all resistors. 40

8. The combination with a plurality of resistors having a common terminal, of a plurality of switching devices adapted to be connected to different tap-points of each of said resistors, a plurality of sets of 45 switches adapted to be connected to different groups of said devices, each switch in said sets having one terminal connected to one end of the corresponding resistor, the switches in each of said sets being alternatively closed and the sets together with said devices being progressively closed to effect 50 gradual short-circuit of all resistors. 55

9. The combination with three star-connected resistors, of a plurality of switching devices adapted to be connected to successive tap-points of each of said resistors, a pair of switches adapted to be connected to alternately-located devices, each pair of switches having a common terminal connected to the outer end of the corresponding resistor, the switches in each pair being alternatively closed and the pairs together with said devices being progressively closed 60 to effect gradual short-circuit of all resistors. 65

In testimony whereof, I have hereunto subscribed my name this 30th day of April, 1920.

LLOYD J. HIBBARD.
